Claims priority, application Canada May 5, 1967

Term of patent 14 years

Int. Cl. D19—05, 08

U.S. Cl. D25—1

FIGURE 1 is a front plane view of a sliding-card locator map bearing the design;

FIGURE 2 is a front elevation;

FIGURE 3 is a side elevation;

FIGURE 4 is a rear plan view; and

FIGURE 5 is a top plan view of an alternate embodiment of the design of FIGURE 1 with cut-away corners.

The characteristic feature of my design resides in the two parallel guide channels which are of a greater length than that of the vertical connecting bar in combination with the map card slidably retained therein.

I claim:

The ornamental design for a sliding-card locator map, as shown and described.
